UNITED STATES PATENT OFFICE

LAWRENCE PAULSON AND ALPHONSE W. ROETTGER, OF ROTHSAY, MINNESOTA

TRAIN ORDER HOLDER

Application filed April 22, 1930. Serial No. 446,380.

This invention relates to new and useful improvements in train order holders and has for its primary object to provide, in a manner as hereinafter set forth, a device of this character which is adapted to support the usual order retaining hoop or ring in a position to be conveniently removed by a person in the cab of a locomotive, thus eliminating the necessity of a person standing dangerously close to the oncoming train and also making it unnecessary for the engineer or fireman of the train to climb down the steps of the locomotive in order to get the order.

Another important object of the invention is to provide a train order holder of the character described embodying a plurality of double ended pairs of resilient clamps adapted to releasably retain an order holder in either end portion.

Further objects of the invention are to provide a train order holder which will be simple in construction, strong, durable, efficient in its use and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:—

Figure 1 is a view principally in side elevation and partly in section of a train order holder constructed in accordance with this invention.

Figure 2 is a detail sectional view showing the construction and mounting means of one of the beveled clamps.

Figure 3 is a horizontal cross sectional view taken substantially on the line 3—3 of Figure 1 looking in the direction indicated by the arrows.

Referring to the drawings in detail, it will be seen that the reference numeral 1 designates a vertically disposed standard or post which is rigidly mounted in the supporting base 2. Secured in vertically spaced relation in the upper portion of the

standard or post 1 and extending diagonally upward therefrom is a pair of arms 3 which are parallel with respect to each other. Mounted on each of the arms 3 in longitudinally spaced relation is a pair of double spring controlled clamps 4 adapted to releasably engage the handle portion 5 of the order holding hoops or loops 6 and as said clamps are identical in construction, a detailed description of one will suffice for all.

Each of the clamps 4 includes a pair of opposed metallic bars 7 and 8, the opposite end portions of which are laterally offset in a manner to provide the opposed, parallel gripping jaws 9 and 10 respectively. The bars 7 and 8 are slidably mounted on a headed, threaded bolt 11 which extends transversely through the arms 3 and has threaded thereon a retaining nut 12. A coil spring 13 is compressed on the bolt 11 between the head 14 thereof and the bar 8. The purpose of the spring 13 is to yieldingly urge the bars 7 and 8 toward the arms 3 and consequently yieldingly urge the jaws 9 and 10 together. The bar 8 is provided with an opening 15 through which slidably projects a guide pin 16 mounted on the bar 7 and said guide pin retains the bars 7 and 8 in parallelism with each other. The free end portions of the jaws 9 and 10 are turned outwardly at an obtuse angle to facilitate the insertion of the handle 5 therebetween.

The train order holders are mounted in the clamps in the manner clearly illustrated in Figure 1 of the drawings. It will also be readily apparent that an order holder may be mounted in the upper jaws of the pairs of clamps.

It is believed that the many advantages of a train order holder constructed in accordance with this invention will be readily understood, and although the preferred embodiment of the invention is as illustrated and described, it is to be understood that changes in the details of construction may be had which will fall within the scope of the invention as claimed.

What is claimed is:—

1. A train order holder of the character

- described comprising a supporting arm, and a pair of double clamps mounted in spaced relation on the arm, each of said clamps comprising a headed bolt mounted on the 5 arm, a pair of opposed bars slidably mounted on the bolt and having their opposed end portions formed to provide co-acting jaws and resilient means engaged with one of the bars in a manner to yieldingly urge the 10 same toward the other bar and further adapted to yieldingly urge said other bar into engagement with the supporting arm.
2. A train order holder of the character described comprising a supporting arm, and 15 a pair of double clamps mounted in spaced relation on the supporting arm, each of said clamps comprising a headed bolt mounted transversely in the supporting arm, a pair of elongated bars slidably mounted on the 20 bolts between the head thereof and the supporting arm, the opposite end portion of each of said bars being laterally offset in a manner to provide co-acting clamping jaws, and a coil spring mounted on the bolts and 25 having one end impinged against the head thereof and its opposite end impinged against the outermost bar in a manner to urge said bar toward the innermost bar and to yieldingly retain the innermost bar in 30 engagement with the supporting arm.
3. A train order holder of the character described comprising a supporting arm, and a pair of double clamps mounted in spaced relation on the supporting arm, each of 35 said clamps comprising a headed bolt mounted transversely in the supporting arm, a pair of elongated bars slidably mounted on the bolts between the head thereof and the supporting arm, the opposite end portion 40 of each of said bars being laterally offset in a manner to provide co-acting clamping jaws, and a coil spring mounted on the bolts and having one end impinged against the head thereof and its opposite 45 end impinged against the outermost bar in a manner to urge said bar toward the innermost bar and to yieldingly retain the innermost bar in engagement with the supporting arm, said outermost bar being provided 50 with an opening, and a guide pin mounted on the other bar and projecting slidably through the opening and constituting means for retaining the bars in parallelism with respect to each other.
- 55 In testimony whereof we affix our signatures.
